CLAIM

The ornamental design for a video game controller, as shown and described.

DESCRIPTION

The present design relates to an ornamental object that can be used as an input device for computer programs.

FIG. 1 is a top plan view of a video game controller;

FIG. 2 is a bottom plan view thereof;

FIG. 3 is a left side elevational view thereof;

FIG. 4 is a right side elevational view thereof;

FIG. 5 is a front elevational view thereof; and,

FIG. 6 is a rear elevational view thereof.

The broken line showing the port and the LED's is included for the purpose of illustrating environmental structure and forms no part of the claimed design.
